UNITED STATES PATENT OFFICE

2,282,734

VENTING DEVICE FOR RADIATORS

William J. Masoner, Chicago, Ill., assignor to The Dole Valve Company, Chicago, Ill., a corporation of Illinois

Application May 25, 1936, Serial No. 81,596

4 Claims. (Cl. 137—122)

This invention relates to improvements in venting devices for radiators and has for its object to provide a new and improved device of this description.

The invention has as a further object to provide a venting device particularly adapted for convector radiators. The invention has as a further object to provide a venting device for concealed radiators. The invention has as a further object to provide a venting device for hot water radiators, which indicates when the radiator has been completely vented so that the vent can be closed before the water is discharged from the device. The invention has as a further object to provide a venting device for concealed radiators which is itself concealed and which indicates when the radiator has been properly vented. The invention has as a further object to provide a venting device arranged so that any water passing through the venting device will be properly taken care of and evaporated so that the device requires no attention on account of this water. The invention has further objects which are more particularly pointed out in the accompanying description.

Referring now to the drawing, Fig. 1 is a view showing a concealed radiator with one form of the venting device in position;

Fig. 2 is an enlarged view taken on line 2—2 of Fig. 1;

Fig. 3 is a sectional view taken on line 3—3 of Fig. 2;

Fig. 4 is an enlarged sectional view taken on line 4—4 of Fig. 1;

Fig. 5 is an enlarged view as seen from the line 5—5 of Fig. 1.

Like numerals refer to like parts throughout the several figures.

In the use of convector heating systems, such as hot water heating systems, the radiators must be vented of air at intervals, in some cases one or more times a week. This venting must be done by unskilled persons, is a disagreeable job under the present conditions and is therefore neglected, causing the heating systems to be inefficient and causing numerous complaints. Furthermore it is a common practice to conceal the radiators and so the venting device is concealed and inaccessible. It often happens that there is water in the vent pipe and the party opening the valves, seeing the water discharge, thinks that no venting is necessary, whereas a large part of the radiator may be ineffective because of the air therein. With the present systems of this type, there is forced circulation of the water, as by

means of pumps, and hence if the vent is held open too long considerable amounts of water may be discharged from the system. The present construction provides a venting device which avoids these and other difficulties.

There is illustrated in the drawing a portion of a heating system wherein concealed radiators are used. Fig. 1 illustrates one of these concealed radiators 1 located in a recess or alcove 2 and provided with a concealing panel 3. The radiator is mounted upon suitable supports 4 and is supplied with heating liquid through the pipe 5. The concealing panel is preferably provided at the bottom with an air admission opening 6 and at the top with an air discharge opening 7. There is a regulating device 8 for the discharge opening 7, by means of which the amount of heated air entering the room is regulated, the regulation being secured by moving the regulating device 8 to close off more or less of the opening 7. At the upper part of the radiator, where the air collects, a vent opening is provided. Connected with the vent opening is a pipe 9. This pipe may be connected therewith in any desired manner, as for example by a pressure coupling 10, see Fig. 4. The pipe 9 preferably extends upwardly to a point below the discharge opening 7 and is connected with a vent valve device having a hollow body portion 11 containing a vent valve member 12 which controls the passageway 13 connected with the pipe 9. Surrounding the passageway 13 is a valve seat 14 and the valve member 12 is provided with a seat engaging portion 15 which engages this valve seat to close the passageway 13 and prevent any discharge from the radiator therethrough. The valve member 12 is provided with a suitable packing 16 which is compressed and held in place by the packing nut 17. Some means is provided for preventing the withdrawal of the valve member 12 and in the construction shown this result is secured by having a shoulder 12a engage the packing washer 16a when the valve has been moved to its open position. The valve member 12 may be provided with a quadruple thread 12b to speed up the opening and closing.

Surrounding the outer end of the valve member 12 is a hollow threaded member 18 threaded to the body portion 11 and which is provided with a head or flange 19. The valve device is supported in position by providing an opening in the concealing panel 3 of sufficient size for the body of the hollow threaded member 18 to pass therethrough and then clamp the portion of the concealing panel surrounding the opening, between

the flange 19 and the end of the body portion 11 and in the space 20, see Fig. 2. It will thus be seen that by tightening up the hollow threaded member 18 the valve device can be tightly clamped to the concealing panel so as to be held in position. The end of the valve member 12 which projects through the panel 3 is preferably non-circular, as shown in Fig. 5, so that the valve member may be easily turned to open or close it. The other end may be supported on the pipe 9 and the radiator 1. This valve device may be placed in any desired position, but is preferably placed below the discharge opening 7 and in a place where the end of the valve member 12 is conveniently accessible from the outside of the concealing panel 3.

There is preferably connected with the body portion 11 a tank or receptacle 21 with which the pipe 9 communicates through the passageway 13 and the hollow of the body portion 11 and the passageway 22. The tank 21 is held in position in any desired manner and as herein shown is attached to an annular member 23 on the body portion 11. In the particular construction shown the end of the tank fits into this annular member as shown. The tank is provided at the top with an opening 24.

Associated with the vent valve is a signaling device which is acted upon by the air discharged from the radiator, so as to give an indication that the air is being discharged. As herein shown this signaling device consists of a noise producing device, such as a whistle 25, which may be attached in any desired position where the air escaping from the radiator will act upon it. As herein shown, this noise producing device has its end inserted in a recess in the body portion 11 and may be held in position by means of solder or the like 26. This noise producing device may be of any suitable form, construction and size to give the proper indicating signal. The air and water passing through the body portion 11 passes through an opening 27 in the noise producing device. This opening may be provided in any desired manner. As herein shown, the noise producing device is hollow and has an opening 28 in its side and there is a plug 29 in the end nearest the body portion 11. The opening 27 may be provided by having a portion of the plug removed at that point. By means of this construction any water which enters the tank 21 will be evaporated and pass out through the opening 24, the heat from the radiator assisting in this evaporation.

I prefer to provide means for preventing foreign matter from entering the pipe 9 and the valve device at the end thereof. One means for securing this result consists in providing a strainer 30 which may be attached to the end of the coupling 10 so as to project into the radiator 1. The coupling 10 may be recessed at the lower end and the strainer inserted in this recess and fastened thereto in any desired manner, as illustrated in Fig. 4.

It will be noted that with this construction there is nothing unsightly protruding into the room beyond the concealing panel and that the only thing that can be seen from the room is the end of the flange 19.

The openings 6 and 7 are preferably provided with ornamental grilles 6a and 7a which may correspond with the decoration of the room. It will be seen that by means of this invention there is no interference whatever with the decoration of the room with which the radiator or radiators are associated, for the panel can be decorated as

desired and in substantially the same way that it could be decorated if there was no radiator back of it, and there are no access doors which would mar the effect of the decoration.

5 The use and operation of my device are as follows.

When it is desired to vent the radiator, the valve member 12 is turned by someone in the room on the outside of the panel 3 by means of a suitable tool or key fitting over the non-circular end of the valve member, and this moves the valve member to its open position, as shown in Fig. 2. It will be seen that during this operation the party opening the valve cannot see what is happening, the parts of the venting device being concealed back of the panel 3. If there is any water in the pipe 9, it will be forced through the body portion 11 and the noise producing device 25 into the tank 21. After the water has been discharged, the air in the radiator will pass through the pipe 9 and through the body portion 11 and through the noise producing device 25 and produce a noise. The party controlling the valve member 12 will then know that air is being discharged from the radiator. When all of the air is discharged, water will pass from the pipe 9 through the body portion 11 and noise producing device 25 and the noise, whether a whistle or other noise, will cease. The party manipulating the valve member 12 will then know that all of the air is out of the radiator and will then close the valve member 12. Usually there will only be a small amount of water discharged into the tank 21 at any venting operation and this small amount, being in a heated chamber, will be evaporated quickly so that under normal conditions it will be properly taken care of and the tank will never be filled to overflowing.

40 It will therefore be seen that by means of this device the air can be easily, quickly and satisfactorily discharged from the radiators and that even when the venting device is concealed, so that the party venting the radiator cannot see what is happening, the air can be vented properly without discharging water into the room or into the recess 2.

45 I claim:

1. An air venting device for hot water systems, comprising a casing through which the air from the radiator is discharged, a valve in said casing for controlling the discharge of air from the casing, a signaling device associated with said casing and actuated by the air discharged from said casing, a valve stem for said valve, a support through which said valve stem passes, and a clamping device connected with said valve casing having separated clamping elements between which a portion of said support is received, for clamping it upon said support with the valve stem exposed through the support.

50 2. An air venting device for hot water systems, comprising a casing through which the air from the radiator is discharged, a valve in said casing for controlling the discharge of air from the casing, a signaling device communicating with said valve casing and actuated by air escaping from the valve casing, a concealing panel for said valve casing and signaling device, having an opening therein, a fastening member on the outside of said concealing panel and having a projecting part which projects through said opening and engages said casing, said casing and fastening member having engaging parts which engage said panel so as to removably clamp it between them, and a valve stem for said valve, said fastening de-

vice having an opening into which the end of the valve stem is received.

3. An air venting device for hot water systems, comprising a casing through which the air from the radiator is discharged, a valve in said casing for controlling the discharge of air from the casing, a signaling device connected with said casing and actuated by the air discharged from the casing, and a receptacle attached to said casing, for receiving water that may be discharged from the casing, said signalling device being located on said casing.

4. An air venting device for hot water systems,

comprising a casing through which the air from the radiator is discharged, a valve in said casing for controlling the discharge of air from the casing, a signaling device connected with said casing and actuated by the air discharged from the casing, and a receptacle attached to said casing, for receiving water that may be discharged from the casing, said signalling device being located on said casing, said receptacle extending laterally from said casing and being provided with an opening at the top by means of which the sound from the signaling device may be easily heard.

WILLIAM J. MASONER.
